F. B. LITTLE

MUSICAL SOUND PRODUCING INSTRUMENT

Filed Oct. 17, 1927

Inventor:
Frederick B. Little
By G. A. Bragg Atty.

UNITED STATES PATENT OFFICE.

FREDERICK B. LITTLE, OF CHICAGO, ILLINOIS, ASSIGNOR TO J. C. DEAGAN, INC., OF CHICAGO, ILLINOIS, A CORPORATION OF ILLINOIS.

MUSICAL-SOUND-PRODUCING INSTRUMENT.

Application filed October 17, 1927. Serial No. 226,745.

My invention relates to sound producing instruments which employ sound producing bars which may be struck by hammers or otherwise set into vibration.

5 The invention has for one of its objects the provision of an improved sound damper for the sound producing bar of such an instrument.

In carrying out this feature of my invention the sound damper bears against the upper end of the sound producing bar, the bar being preferably suspended and bearing the weight of the damper. I also employ an electromagnet which includes two 15 elements, one an energizing winding, and the other, an armature, one of these elements being carried by said damper and both being relatively disposed to lift the damper when the coil is energized. A mounting is desirably provided for the other one 20 of said electromagnet elements and said bar and upon which this electromagnet element and bar are adjustable toward and from the hammer.

25 In the preferred embodiment of the invention the winding is in the form of a normally stationary solenoid coil and the armature is in the form of a core carried by the sound damper and entering the bore of the coil.

The invention also has for its object the provision of an improved suspension for the sound producing bar. In carrying out this feature of the invention the bar is suspended 35 from a bail and a carrier is provided for the bail, having aligned grooves which receive side portions of the bail and which carrier is received in the bight of the bail that is angularly deflected from the side portions of the bail. This carrier desirably also carries the solenoid coil, previously referred to.

I will explain my invention more fully by reference to the accompanying drawing in which Fig. 1 is a side view of the preferred 45 embodiment of the invention with portions broken away and other portions shown in section, one form of a circuit arrangement being also illustrated; Fig. 2 is a plan view of the structure shown in Fig. 1; Fig. 3 is 50 a side view of a portion of the structure shown in Fig. 1; and Fig. 4 is an end view of a part of the structure with a portion shown in section.

The instrument illustrated is a percussion 55 instrument employing a hammer and a vi-

brating bar which may be struck by the hammer when a sound is to be produced by the bar, both the bar and hammer having a common support. The hammer illustrated includes a rod having a rear portion 1 which is made of iron and constitutes the core of a solenoid coil 2. There is another rod portion 3 which is supplied in addition to the rod portion 1 and is of smaller diameter. This rod portion 3 is at that end 60 of the solenoid coil in the direction of which the core element 1 is moved when the solenoid coil is energized, upon the closure of the switch 4 that serves to include the suitable source of current 5 in the circuit of the 65 solenoid coil.

The coil is carried by a bracket 6 which is mounted upon a suitable support 7, said bracket being forwardly extended at 8 to also serve as a support for the bail 9 usually a 70 fiber string or cord, for the tubular bell 10 or other sound producing element. A hammer head 11 is provided upon the rod 3 and serves to strike the bell 10 each time the switch 4 is closed, the hammer mechanism being desirably of the construction set forth in my copending application Serial Number 226,747, filed Oct. 17, 1927.

The sound damper 12 may be in the form of a pad. It is arranged above the 85 elongated sound producing bar 10 and bears against the upper end of this bar, the weight of the sound damper being borne by the bar. The sound damper is mounted upon a disc 13 which may be of non-magnetic metal. This disc and the sound damper carry an iron core 14 which is arranged within the bore of a solenoid coil 15. This solenoid coil is housed within a casing 16 that also constitutes a carrier for the coil. 90 This casing is provided with a block formation 17 upon its top side, this block formation being disposed within a slot 18 which is elongated in the direction of the bracket portion 8. A threaded stem 19 is carried by 100 and projects upwardly from the block portion 17. A washer 20 loosely surrounds the stem 19 and is clamped against the top of the bracket portion 8 by the nut 21 that is screwed upon the stem 19. The side portions of the bail 9 are passed downwardly through the upright grooves 22 that are formed in fins that are provided upon diametrically opposite side portions of the carrier 16. The bight of the bail is angularly 110

deflected with respect to the angular side portions thereof and receives the carrier 16.

It will be observed, from the present construction illustrated and described, that the sound dampener floats with respect to the solenoid coil and that the sound dampening influence thereof is effected by the weight thereof supplemented by the weight of the parts 13 and 14 carried thereby. To 10 adjust the position of the sound producing bar 10 toward and from the hammer, the nut 21 is loosened and the carrier 16 is moved toward or from the hammer as desired. The positioning of the carrier 16 at 15 the same time secures a corresponding position of the sound dampener, the electro-magnet, the bail 9, and the sound producing bar supported by the bail, all of these parts remaining in proper cooperation irrespective 20 of the position of the carrier 16 upon the bracket portion 8.

Changes may be made without departing from the invention.

Having thus described my invention, I claim:

The combination with an elongated sound producing bar; of a hammer mounted upon one side of said bar and operable to strike the bar to set it into vibration; a sound dampener bearing against the upper end of the bar and whose weight is borne by the bar; a solenoid including one element in the form of a hollow energizing winding and another element in the form of a magnetizable core received in the interior of said winding, the winding being normally stationary and the core being movable and coupled with the dampener; and a mounting for the electromagnet winding and bar and upon which this electromagnet element and bar are adjustable toward and from the hammer.

In witness whereof, I hereunto subscribe my name.

FREDERICK B. LITTLE.
